UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

PRESSER-FOOT FOR SEWING-MACHINES.

1,294,226.

Specification of Letters Patent. Patented Feb. 11, 1919.

Application filed December 30, 1916. Serial No. 139,820.

To all whom it may concern:

Be it known that I, JOSEPH BERGER, Jr., a citizen of the United States, residing at Utica, in the county of Oneida, State of New York, have invented certain new and useful Improvements in Presser-Feet for Sewing-Machines, of which the following is a description, reference being had to the accompanying drawing and to the figures 10 of reference marked thereon.

The invention relates to new and useful improvements in a presser foot for sewing machines, and more particularly to a presser foot which is adapted to guide and overlap 15 the edges of fabric sections whereby the same may be united to form a seam.

An object of the invention is to provide a presser foot which is so constructed as to receive the up-turned edges of fabric 20 sections whereby they may be trimmed and prepared for overlapping and uniting, which presser foot is also so constructed as to return the up-turned trimmed portions of the fabric sections to the plane of the fabric sections in overlapped relation to each other 25 with means for positively insuring that the edge of the upper portions of the fabric sections shall lie within the limits of the stitching mechanism.

30 A further object of the invention is to provide a presser foot of the above character with a portion thereof in front of the needle opening projecting below the remainder of the surface of the presser foot 35 and adapted to coöperate with the depression in the throat plate for guiding the fabric section having the lower overlapped portion in a plane below the fabric section having the upper overlapped position so as 40 to facilitate the overlapping of the fabric sections.

45 A still further object of the invention is to provide a presser foot of the above character with a main section and an auxiliary yielding section arranged side by side and adapted to engage, respectively, the fabric sections which are to be united, and also to provide said main section with a yielding part located wholly in front of the needle 50 opening in the presser foot.

These and other objects will in part be

obvious and will in part be hereinafter more fully disclosed.

In the drawings, which show by way of illustration one embodiment of the invention:—

Fig. 1 is a top plan view of a presser foot embodying the improvements;

Fig. 2 is a bottom plan view of the same;

Fig. 3 is a perspective view of one section of the presser foot;

Fig. 4 is a perspective view of the other section of the presser foot;

Fig. 5 is a perspective view showing the presser foot in its relation to the needles, the cross thread stitching mechanism and the work support;

Fig. 6 is a view showing, partly in section and partly in side elevation, my improved presser foot and its relation to the needles and the work support;

Fig. 7 is a perspective view showing the under face of the presser foot;

Fig. 8 is a sectional view on the line 8—8 of Fig. 1;

Fig. 9 is a sectional view on the line 9—9 of Fig. 1;

Fig. 10 is a sectional view on the line 10—10 of Fig. 1;

Fig. 11 is a longitudinal sectional view on the line 11—11 of Fig. 2.

My improved presser foot is especially adapted for use in the joining by stitching of overlapped fabric sections. The edge portions of the fabric sections to be joined are turned out of the plane of the fabric sections, and these up-turned portions are placed side by side and directed into a slot in the presser foot which extends from the front end of the presser foot to a point slightly in advance of the needle opening. A trimming mechanism, including horizontally disposed trimming blades, is adapted to trim the edge portions lead along the slot. The presser foot is provided with a guiding projection extending laterally into the slot and located in rear of the trimming mechanism which operates to positively overlap the edge portions after they are trimmed. The presser foot is also provided with means for insuring that the edge of the upper overlapped portion shall

lie wholly within the limits of the stitching mechanism so that it will be fully covered. The presser foot is further provided with an auxiliary yielding section 5 which has a portion projecting below the main surface thereof which is adapted to coöperate with the depressed section in the throat plate for guiding one of the fabric sections in a lower plane than the other for 10 facilitating the overlapping of the sections. The presser foot also has a yielding section in the main section of the foot located in advance of the needle opening which coöperates in guiding the material when 15 passing over cross seams.

Referring more in detail to the drawings:—

The improved presser foot consists of a supporting shank 1 which is adapted to be 20 attached to the presser bar 2. The foot portion of the presser foot is formed into two sections, a main section 3 which is rigidly connected with the shank 1 and an auxiliary section 4 which is yieldingly connected thereto. Said shank 1 is provided with spaced lugs 5 and 6 between which the shank 7 of the auxiliary section 4 slides. The cap plate 8 holds the shank 7 of the auxiliary presser foot in place. A spring 9 25 carried by the shank 1 rests in a groove 10 in the upper end of the shank 7 of the auxiliary section of the presser foot and normally forces said section downwardly. Said shank 7 is formed with a vertical slot 11 30 through which a pin 12 extends for limiting the downward movement of the auxiliary section 4. The sections of the presser foot are cut-away or separated so as to form a slot 13 which is adapted to receive the up- 35 turned edges of the fabric sections.

In Fig. 5 of the drawings, I have shown two fabric sections, indicated at F and F', respectively. The edge portions are turned up, as indicated at f and f', and these up-turned edges are directed into the slot 13. Mounted on the presser foot is a fixed trimming blade 14. Coöoperating with this fixed trimming blade is a movable trimming blade 15. This forms a horizontal trimming 40 mechanism which trims the up-turned edges.

The main section 3 of the presser foot is formed with an opening 16 for the needles of the stitching mechanism. The throat plate 17 has a depressed section 18, and the auxiliary section 4 of the presser foot has a portion 19 which extends below the lower face of the section 4 and into this depressed section 18 of the throat plate. The throat plate 17 is formed with a rib or fin 20 which 45 extends into the slot 13 and serves to direct the up-turned edges of the fabric sections into said slot. The depressed section 18 terminates just in front of the needles, as is clearly shown in Fig. 6 of the drawings.

As the fabric sections leave the trimming

mechanism, one section is in a plane slightly above the other and the up-turned edge f' is supported by the rib 20.

The auxiliary section 4 of the presser foot has a laterally projecting fabric guide 21 which extends into the slot 13. The edge of the auxiliary section and this fabric guiding member 21 are so shaped that the fabric portion f after it is trimmed is crowded down underneath the fabric portion f' 75 which is held raised by the rib 20. The edge portion f' passes over this guiding member 21. The main section 3 of the presser foot has a laterally projecting fabric guide 22 which extends into the slot 13, and the front curved edge 23 of this fabric guiding member turns down the edge portion f' onto the turned down portion f. The auxiliary section 4 has a vertically extending part 24 which fits in a cut-away section 25 85 of the main presser foot section and forms a part of the wall of the needle opening. This part 24 is of sufficient height so as to extend above the lower face of the main section of the presser foot even when the auxiliary section is depressed to its full extent. The part 24 serves to keep the edge of the fabric portion f' well within the limits of the stitching mechanism.

From the above, it will be apparent that 95 my improved presser foot is constructed so as to positively turn down one of the up-turned trimmed edge portions, and then turn down the other trimmed edge portion onto the first-named edge portion so that 100 when the edge portions are brought back into the plane of their respective fabric sections they are overlapped, and this occurs before they cross the needle opening in the presser foot. The main section 3 of the 105 presser foot is formed with a yielding section 25. This yielding section 25 is carried by a post 27 attached to a spring 28 which forces said yielding section 25 downwardly to a limited extent. This yielding section 110 25 terminates just in rear of the trimming mechanism, and the purpose of said yielding section is to engage a fabric section in front of the needles when the main section of the presser foot is raised by a cross seam passing 115 underneath the same. This insures that the fabric sections will be properly held and directed to the trimming mechanism when cross seams are passing underneath the presser foot.

It will be noted that the fabric guide 22 is carried by the section 3 of the presser foot while the fabric guide 21 is carried by the section 4 and that these sections yield relative to each other. If two thicknesses of 125 fabric pass under the main section 3 or a cross seam passes underneath this section, it will rise, while the section 4, being independently mounted, will remain on the single thickness of fabric and this results in 130

separating the guides 21 and 22 to permit the extra thickness of fabric to pass through the guide passage formed by these guides 21 and 22 without in any way choking or clogging the passage. In other words, I have in substance, a guide channel which varies in width as the thicknesses in the fabric sections passing underneath the main foot vary.

10 It is obvious that minor changes in the details of construction and the arrangement of parts may be made without departing from the spirit of this invention as set forth in the appended claims.

15 Having thus described the invention, what is claimed as new is:—

1. A presser foot for sewing machines including in combination, a foot portion having a needle opening and a slot in front of 20 the needle opening leading from the front end of the presser foot to a point in advance of the needle opening, said slot being adapted to receive up-turned edge portions of fabric sections which are to be trimmed, 25 means carried by the presser foot for returning the trimmed edge portions to flat and overlapped relation before they cross the needle opening, and means located in advance of the needle opening and adjacent 30 thereto for engaging the edge of the upper trimmed portion for guiding said edge whereby the same will be directed within the limits of the stitching mechanism.

2. A presser foot for sewing machines including in combination, a foot portion having a needle opening and a slot extending from the front end of the presser foot to a point in front of the needle opening whereby up-turned edge portions of fabric sections 35 may be directed and trimmed, means for overlapping the trimmed edge portions before they cross the needle opening, said presser foot having a portion in front of the needle opening and at one side of the slot 40 projecting below the remaining surface of the presser foot and adapted to coöperate with a depressed portion in the throat plate so that the fabric section engaged thereby 45 will be lead under the presser foot in a plane lower than the other fabric section for the 50 purpose described.

3. A presser foot for sewing machines including in combination, a foot portion having a main section and an auxiliary yielding 55 section, said main section having a needle opening therein, said sections being spaced in front of the needle opening to form a slot extending from the front end of the foot to a point in front of the needle opening, said 60 slot being adapted to receive up-turned edge portions of fabric sections which are to be trimmed, said presser foot having means for returning the up-turned edge portions to flat and overlapped relation before they 65 cross the needle opening, said main section

of the presser foot having a vertically extending portion adjacent the inner end of the slot for guiding the edge of the upper overlapped portion so as to insure said edge passing within the limits of the stitching 70 mechanism.

4. A presser foot for sewing machines including in combination, a foot portion having a main section and an auxiliary yielding section, said main section having a needle 75 opening therein, said sections being spaced in front of the needle opening to form a slot extending from the front end of the foot to a point in front of the needle opening, said slot being adapted to receive up-turned edge portions of fabric sections which are to be trimmed, said presser foot having means for overlapping the up-turned edge portions before they cross the needle opening, said auxiliary section having a portion 80 thereof in front of the needle opening projecting below the main surface of the auxiliary section and adapted to coöperate with a depressed section of the throat plate for guiding the fabric section engaged thereby in a plane lower than the other fabric section to facilitate the overlapping of the fabric sections.

5. A presser foot for sewing machines including in combination, a foot portion having a main section and an auxiliary yielding section, said main section having a needle 95 opening therein, said sections being spaced in front of the needle opening to form a slot extending from the front end of the foot to a point in front of the needle opening, said slot being adapted to receive up-turned edge portions of fabric sections which are to be trimmed, said presser foot having means for overlapping the up-turned edge portions before they cross the needle opening, said auxiliary section having a portion 100 thereof in front of the needle opening projecting below the main surface of the auxiliary section and adapted to coöperate with a depressed section of the throat plate for guiding the fabric section engaged thereby in a plane lower than the other fabric section to facilitate the overlapping of the fabric sections, said main section of the presser foot 105 having a yielding portion located in front of the needle opening and adapted to coöperate with the auxiliary section in holding the fabric sections when cross seams are 110 passing beneath the presser foot.

6. A presser foot for sewing machines including in combination a foot portion having a needle opening and a slot in front of the needle opening leading from the front end of the presser foot to a point in advance 125 of the needle opening, said presser foot being divided longitudinally so that the sections of the foot on opposite sides of the slot may yield independently, guides carried by said respective sections for return- 130

ing the trimmed edge portions to flat and overlapped relation before they cross the needle opening, said guides being so disposed that the movement of one section of the foot relative to the other caused by the varying thicknesses of fabric in the respective fabric sections being joined will cause the guiding channel between said devices to

vary to accommodate the increased thickness in the fabric sections. 10

In testimony whereof, I affix my signature, in the presence of two witnesses.
